CLAIM

The ornamental design for a disposable ingredient cartridge for a bread machine, as shown and described.

DESCRIPTION

FIG. 1 is a bottom perspective view of a disposable ingredient cartridge for a bread machine;

FIG. 2 is a top perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines and the unshaded areas in between the broken lines depict portions of the disposable ingredient cartridge for a bread machine that form no part of the claimed design.

1 Claim, 8 Drawing Sheets
